UNITED STATES PATENT OFFICE

2,173,123

RAILWAY BLOCK SYSTEM AND POWER
SUPPLY CIRCUIT

John C. McDonald, Beechhurst, Long Island, N. Y.

Application February 11, 1938, Serial No. 190,121

10 Claims. (Cl. 246—34)

My invention relates broadly to railway train control and signalling systems and more particularly to an automatic voltage regulating circuit in a railway block system.

5 One of the objects of my invention is to provide a simplified railway block signal system employing a minimum of component parts, and which is relatively inexpensive and simple to maintain, with dependability and safety more fully achieved than has heretofore been obtained.

Another object of my invention is to provide a track signal control circuit having automatic voltage regulation so that extended track sections may be employed without altering the voltage of the supply, and operation at low voltage in the track circuit may be effected.

Still another object of my invention is to provide signal means in combination with the automatic voltage regulating circuit at the exit of a block, for signalling workers in the vicinity of a train in the block ahead.

A further object of my invention is to provide a block signal system for railroads and special voltage supply circuits for the track in the several blocks adaptable to blocks of indefinite length for coordination with modern high speed train operation.

A still further object of my invention is to provide low power apparatus for standard use regardless of the length of track section to be fed, the voltage applied to the rails being of low value and automatically controlled in accordance with track conditions in the section or block.

35 Still another object of my invention is to provide a control circuit which avoids the use of current limiting reactors, such as are ordinarily employed to prevent excessive currents in the rails when a section is occupied, and which result in low power factor conditions in the supply under load. I provide instead a voltage regulating circuit by which the current in the tracks is reduced to substantially zero under short circuit conditions, with the track section occupied, so that apparatus of low current rating may be employed.

Another object of my invention is to provide a voltage regulating circuit in the supply systems of train control relays and the cab signal circuits as well as in the track signal control circuit, which insures uniformity in the system and simplicity in operation and maintenance, as will be understood from the following specification.

Other and further objects of my invention reside in the circuits and arrangements herein-

after more fully set forth, with reference to the accompanying drawings, in which:

Figure 1 is a schematic diagram of the track and wayside control circuits; Fig. 2 is a schematic diagram of the cab signal and control circuits embodying my invention; and Fig. 3 is a modified form of track circuit for speed control in isolated blocks.

This invention is an improvement in the automatic train control and signalling systems disclosed in my copending application Serial Number 117,929, filed December 28, 1936, now Patent 2,110,960, the improvements relating particularly to the voltage regulation circuits and the signal and control elements directly in connection therewith. In order that my invention may be more clearly understood, I have illustrated the major signal and control circuits substantially as shown in my copending application, but with the supply circuits and related signal and control circuits modified in accordance with my present invention.

Track circuits now generally in use broadly consist of a source of current connected with the rails at relatively high voltage through a current limiting impedance. The presence of a train in a section short-circuits the rails and current from the source is limited only by the impedance in the circuit. Such systems commonly require 12 to 18 watts power for each section, and where alternating current is employed with an impedance of low power factor, a one kilowatt transformer in each track circuit is found necessary because of the heating effect of the watt-less current. Furthermore, such track circuits are limited to sections of one to two thousand yards, dependent upon the ballast impedance of the road bed at the relatively high line voltages used. Blocks of this length are inadequate for the present high speed trains, which at speeds of one hundred to one hundred and twenty miles per hour traverse such blocks in approximately twenty seconds. Longer blocks are highly desirable but positive operation must be preserved and low cost and maintenance must be assured. The system of my invention effectively provides for all of this, and may be employed with section lengths several times as long as present sections, where feasible, as in parts of the western United States.

The system of track supply of my invention is based on a voltage regulation circuit involving phase shift in oppositely related current components, the phase shift being provided by impedance in the track circuit. Such impedance is conveniently provided in the inductive react-

ance and the resistance of the winding of the track relay connected at the entrance of a section, and the resistance of the rails and the ballast resistance in the track bed across the ties up to the exit of the section where the source is connected. As the impedance is thus usually inductive, the circuit may be considered as providing a leading voltage at the entrance of the section to draw the current from the source in complement to the pressure character of the voltage at the source. In furtherance of this view, it should be noted that increase in the length of the track section and the increase in resistance thus encountered, result in an increase in the phase shift and greater voltage on the rails so that substantially the same current conditions are maintained independently of the length of the block. When the section is occupied, the factors producing the phase shift are effectively shunted so that the voltage in the rails is reduced substantially to zero, and the current likewise, regardless of the length of the track section. With the low voltage applied to the rails, the ballast resistance through the road bed is high and the current is confined to the rails.

Referring to the drawings in detail, Fig. 1 shows the arrangement of track related apparatus in schematic form. It will be understood that the track sections may be of various lengths and that the connections to the track are made substantially at the entrance and exit ends, as indicated, while the signal and control apparatus is arranged at any convenient or desired location in the track section. The control system is the single line arrangement of my copending application Serial Number 117,929, now Patent 2,110,960, and no other interconnection or intercoupling is employed between sections.

In Fig. 1 I have shown blocks A, B, C and D, the circuits with respect to block B being shown in detail, with connections to the track relay in the forward block C. The direction of the train is from block A towards block D. Corresponding parts in block C are designated by like primed reference characters. In block C, rails 5', 6', are connected with power lines 1 through transformers 2', 3', arranged in a manner to be fully described hereinafter. Also connected with the rails 5', 6', is the winding of relay 7' which is disposed adjacent the entrance of the block C. Relay 7' is normally energized through the rails and is deenergized by the shunt created by presence of a train in the block C. Contacts of relay 7' actuate signal and control means in block B in accordance with track conditions in block C, and also control the operation of speed control means in the block C, through relay 16', similarly as relay 7 in block B controls relay 16 when the relay 16 is conditioned by contacts on relay 7' in accordance with track conditions in block C.

In block B, relay 7 is energized through rails 5 and 6, similarly to relay 7' in block C. This track circuit is a principal feature of my invention and includes two transformers connected in a balanced parallel relation with provision for deriving voltage therefrom for the rails and current for signalling purposes. A transformer 2 has the primary 2a thereof directly connected across the power lines 1; and a similar transformer 3 has the primary 3a thereof connected across the power lines 1 through the rails 5, 6, and the winding of relay 7. The secondaries 2b and 3b are connected with the voltages thereacross in phase opposition for conditions of short-circuit across rails 5, 6; this condition is

indicated at 60 as due to occupation of block B, and the secondary voltages are equal so that no current flows in the secondary loop 2b, 3b. With the block B unoccupied by a train, the rails 5, 6, are not shunted and the track circuit is completed through the winding of relay 7. Inductive impedance found in the rails and the relay winding causes phase shift in the current flowing in the primary 3a of transformer 3, and consequently a shift in the phase of the voltage across the secondary 3b and a current results in the secondary loop 2b, 3b. The windings in the secondary loop are connected in reverse order and in phase opposition, as indicated in the drawings. This current is made available to operate a signal indicator at 4 at the exit end of the block B to indicate clear track to gangs of workmen possibly employed at this location, or in block C, or to a train advancing through block C towards block B which might otherwise meet a train coming from block A in head-on collision. This latter danger is effectively eliminated by the arrangement of my invention as occupied track conditions in the backward block B are indicated forward to block C by the current conditions in the secondary loop 2b, 3b, through indicator 4.

Another indication is afforded by virtue of the current variations in the secondary loop 2b, 3b. Open circuit condition, such as may be caused by a broken rail, results in the removal of voltage at the primary 3a and consequent removal of the bucking voltage in the secondary 3b. The current in the secondary loop 2b, 3b, accordingly increases, through indicator 4, and warns of the faulty track condition which prevents normal operation of the system.

The following data is representative of the track circuit conditions, track unoccupied, under the operation above detailed:

Line voltage	120 volts	40
Relay and track impedance	2 ohms	
Phase shift in primary 3a	1° 10'	
Track voltage	1 volt	
Track current	0.5 ampere	
Secondary loop current	5. amperes	45

With the track occupied, the phase shift is reduced substantially to zero, and the track voltage and current and the secondary loop current likewise. The broken rail, open circuit condition would be somewhat different: track current would be zero and the secondary loop current approximately 10 amperes; while the track voltage would be approximately zero due to the induced voltage in the primary 3a from the secondary 3b, which substantially cancels the line voltage.

The same arrangement may be employed for energizing the speed control elements, as shown in Fig. 1 at transformers 8 and 9, the primary 9a being connected, like the primary 3a, in series with a reactive load 10 across the lines 1. The load 10 is adapted to be shunted by contacts 14 controlled by relay 16 for deenergizing lamps 11 and 12, which are energized by the potential drop across the load 10.

Relay 16 is adapted to effect a quick "break" but slow "make" in the circuits controlled by the contacts of the relay which is energized from the lines 1 through contacts of both relay 7 and relay 7'. There is a direct circuit through one contact 18' and arm 17' on relay 7' to energize relay 16 when block C is unoccupied; but when block C is occupied, contacts 17', 18', are opened and the relay 16 is controlled by contacts 19, 20, and 20a of relay 7 when a train enters block B. When

relay 7 drops, upon occupation of block B by a train, contact arm 19 momentarily opens the circuit to relay 16 causing it to drop and energize lamps 11, 12. The circuit to relay 16 is immediately restored through contact 20a and relay 16 may remake the shunt across load 10 after a predetermined time for transfer of the signal to the train for automatic control of the speed thereof, as will be explained.

10 Wayside signal lamps are shown as green at 50, yellow at 62, and red at 70, of the conventional significance. The green lamp 50 is lighted continuously when block C is unoccupied, through contacts 52', 53', which energize a series circuit including load reactors 51 and 54, lamp 50 being energized by the potential drop across reactor 54. Simultaneously the potential drop across reactor 51 is applied to lamp 58 for actuating a cab signal. The yellow lamp 62 is connected similarly across a reactor 63 in series with reactor 61 and contacts 52', 53a', in relay 1', with control lamp 64 connected across reactor 61. The red lamp 70 is likewise connected across a reactor 71 in series with reactor 69 and contacts 67', 68a', in relay 1', with control lamp 72 connected across reactor 69. Lamps 62 and 70 are thus both lighted with block C occupied and relay 1' dropped, and may be disposed at spaced intervals along block B for proper coordination in the system.

30 The positions of control lamps 11, 12, 58, 64, 72, along the wayside, are determined relatively in different planes with respect to the side of the train so that individually responsive photo-sensitive devices may be provided on the train, as indicated in Fig. 2. The cab circuits shown in Fig. 2 are substantially the same as described in my copending application 117, 929, with the substitution of the power supply circuit hereinbefore described for the supply circuit shown in that application. An alternating current power supply is indicated at 25, feeding lines 26. Transformers 27 and 28 are connected, like transformers 8 and 9, Fig. 1, to provide a potential difference across an inductive load comprising the windings of relays 30, 34. Relay 30 is of the slow "break", quick "make" type, and includes sets of contacts 31 and 32. Relay 34 is conventional and includes contacts 35. Means for short-circuiting the inductive load of relays 30, 34, is provided in contacts 36 controlled by the winding of a relay 38, which also controls sets of contacts 39 and 40.

45 Relay 38 is energized from source 25 through switch contacts 41 of a relay 122, operated from a source 118 through photosensitive device 117 under control of lamps 11, 12, at the wayside. In normal position, as shown, contacts 36, 39 and 40 are open, and the windings on relays 30, 34, are energized. Brake control valves 45 and 46 are provided with release devices normally held closed by current from source 25. The actuating winding in valve 45 is connected through contacts 35 and 31; and the actuating winding in valve 46 is connected through contacts 32. Contacts 35 open immediately upon the operation of the photosensitive device 117 which results in the application of service brakes by means of valve 45 to check the speed of the train.

50 Operation of relay 38 places a shunt across contacts 41 of relay 122 through contacts 39 and a normally closed manual switch 47, thereby holding relay 38 energized. If this shunt is maintained sufficiently long, relay 30 operates to open contacts 32, which results in the application of emergency brakes by means of valve 46. The effect of the opening of contacts 32 may be pre-

vented by manual operation of switch 48 in shunt thereof; and the release of both service and emergency brakes may be effected by operation of switch 47, reenergizing relays 30 and 34. It should be noted, however, that application of the service brakes under control of lamps 11, 12, on the wayside cannot be prevented.

55 The cab circuits for actuating the signal lamps derive power from the source 25 through transformer circuits similar to that of transformers 10 2, 3, and 8, 9, in Fig. 1. Transformers 73 and 74 are connected to provide a voltage across an inductive load comprising the winding of relay 78; and transformers 75 and 76 are connected to provide a voltage across the inductive load including the winding of relay 79. Relays 78 and 79 control the operation of a plurality of circuits through contact arms 85, 89, and 87, 91, respectively.

60 Relay contacts 80 of relay 121, operated from source 118 through photosensitive device 116 under control of lamp 72 at the wayside, are connected in shunt with the winding of relay 79 and when closed cause contact arm 87 to drop, opening a circuit from the source through green signal lamp 84 and contact 88, and closing a circuit through contact 88a and yellow signal lamp 92 to the source. At the same time, contact arm 91 is dropped and a circuit completed through the winding of relay 96, contacts 94 of relay 83, and 30 contacts 95 of relay 102. Operation of relay 96 closes contacts 97 which shunt the contacts 80 through contacts 100 of relay 102, and thus maintains relay 79 deenergized.

65 Relay contacts 81 of relay 120, operated from source 118 through photosensitive device 115 under control of lamp 64 at the wayside, are connected in shunt with the winding of relay 78 and when closed cause contact arm 85 to drop, opening the circuit through contact 86 to contact arm 40 87 of relay 79 and deenergizing yellow lamp 92, and closing a circuit through contact 86a directly to the red lamp 101 for energizing the red signal lamp. At the same time, contact arm 89 is dropped and a circuit completed through the winding of relay 102, contacts 40 of relay 38, and contacts 93 of relay 83. Operation of relay 102 opens contacts 100, removing the shunt on relay 79, and also opens contacts 95 to deenergize directly the relay 96. Contacts 103 are closed to 50 complete a shunt circuit through contacts 98 of relay 96 on contacts 81 and thus maintain relay 78 deenergized. Reenergization of relay 79 does not affect the signal circuits as the red lamp 101 only is connected through contact arm 85 of relay 78.

70 It will be noted that operation of relay 102 depends upon the condition of relay 38 and relay 102 will not be energized if the brake control circuit has already been actuated. The signal 60 circuits thus retain the caution indication of yellow lamp 92, subject to restoration to normal or green lamp signal 84 by operation of contacts 82. Relay 119 is operated from the source 118 through photosensitive device 114 under control of lamp 58, and relay contacts 82 when closed complete the circuit to the winding of relay 83 which operates to open the circuits to relays 96 and 102, deenergizing whichever one, if any, is operative. Relays 78 and 79 thus are restored to 70 operative condition and the green lamp 84 again lights. Operation of the brake control system by contacts 41 and relay 38 may restore the green signal circuit, but as the brakes are automatically applied the signal is disregarded; moreover, if the 75

brakes are released and the train proceeds, other indications may promptly alter the green signal and the brakes may be again applied.

The speed control system may be applied to isolated blocks, independent of the signal system, for controlling the speed of trains on sections of bad road bed, at bridges, curves or grades, in the manner shown in Fig. 3. Double primed reference characters indicate the required elements which are connected and operative in the same respect as described with reference to Fig. 1.

Referring to the system as a whole, Figs. 1 and 2, and considering clear traffic in block C, a train entering block B, as at 60, will find conditions as indicated in Fig. 1; that is, green signal lamp 50 will show lighted at the wayside and control lamp, or lamps, 58 will be lighted at a selected position or positions along the block so that the clear track signal 84 may be maintained in the cab. All other circuits in block B are inoperative as the condition of relay 7' in block C precludes operation thereof.

Considering now that the train has passed into block C, creating a condition for block B of an occupied block ahead. A train entering block B as at 60 will find yellow and red signal lamps lighted at selected positions along the block, and control lamps 64 and 72 operative to actuate the yellow and red signal lamps in the cab as the train passes the control positions. Moreover, control lamps 11 and 12 are energized by the train upon entering the block so that the brake control system in the cab may be operated if the danger conditions ahead remain. The emergency application of brakes would follow unless prevented by the driver, as hereinbefore shown.

Clearance of the section ahead, block C, results in restoration of the green signal at the wayside and operation of control lamp 58 which will convey the signal to the cab as the train passes the control position at reduced speed. If the train has been forced to stop, the wayside signal 50 indicates clear track and the train may proceed. The restoring action of control lamp 58 through relay 119 and contacts 82 is available within block B when block C is cleared before the automatic brake control system is actuated by control lamp 11, 12, and results in showing the green signal 84 in the cab, whereupon full speed may be resumed and the effect of the automatic control prevented by holding the switch 47 open.

I have indicated in the drawings the loop circuits including the secondary windings of each of the transformer circuits in opposed phase, one with respect to the other. It will be understood that instead of connecting the secondary windings in phase opposition, I may connect the primary windings in reverse order or phase opposition. Either method of connection may be employed.

It will be understood that duplicates of all control lamps may be arranged along the block and the relative positions thereof selected in accordance with road conditions for maximum efficiency of operation.

While I have described my invention in certain preferred embodiments, I do not intend that my invention shall be limited thereby and I desire that it be understood that modifications may be made within the scope of the appended claims.

What I claim as new and desire to secure by Letters Patent of the United States is as follows:

1. In a railway block system including a control device having reactive characteristics, a source of alternating current, a transformer having primary and secondary windings, a circuit comprising said source and said primary winding connected in series with said control device, said device being constituted to alter the phase relation of the voltage of said secondary winding, a second transformer having a primary winding directly connected to said source and a secondary winding, connections between terminals of like polarity on said secondary windings, and means for shunting said control device, the voltages of said secondary windings being in phase opposition with said control device shunted by said means. 5 10 15

2. In a railway block system including a control device having reactive characteristics, a source of alternating current, a pair of transformers having primary windings connected with 20 said source and secondary windings, terminals of like polarity on said secondary windings being connected together, said control device connected between said source and one of the primary windings, and means for shunting said control device, said device normally being energized by a voltage resulting from phase shift in the magnetic field of the last said primary winding due to the reactive characteristics of said control device, which voltage is reduced to substantially 25 zero with said device shunted by the said means. 30

3. In combination, a source of alternating current, a pair of transformers each having primary and secondary windings, and an impedance device; connections from one of said primary windings directly to said source; a series circuit including the other of said primary windings, said source and said impedance device; and connections between terminals of like polarity on said secondary windings, said impedance device being energized by a voltage thereacross proportional to the out of phase relation of the voltages of said secondary windings due to the reactance of said device. 35 40

4. In combination, a source of alternating current, a pair of transformers each having primary and secondary windings, an impedance device, and a low resistance shunt circuit connected across said impedance device; connections from one of said primary windings directly to said 50 source; a series circuit including the other of said primary windings, said source and said impedance device; and connection between terminals of like polarity on said secondary windings; said impedance device adapted to be energized by a voltage thereacross proportional to the out of phase relation of the voltages of said secondary windings due to the reactance of said device, which voltage is reduced substantially to zero by the connection of said shunt circuit 60 across said device whereby the reactance of said device is substantially ineffective in said series circuit. 55 65

5. The combination set forth in claim 4 wherein said low resistance shunt circuit comprises a 65 train occupied track section in a railway block signal system, exit of the train from said track section operating to open the shunt circuit across said device.

6. The combination set forth in claim 4 where- 70 in said low resistance shunt circuit comprises a train occupied track section in a railway block signal system, exit of the train from said track section operating to open the shunt circuit across said device; and wherein said impedance device 75

constitutes the operating winding of a relay system adapted to actuate signal and control apparatus in said block system, said device being energized with said track section unoccupied.

5 7. The combination set forth in claim 4 including signal means in one of the connections between said secondary windings responsive to the circulating current in said secondary windings; and wherein said low resistance shunt circuit comprises a train occupied track section in a railway block signal system, exit of the train from said track section operating to open the phase relation of the voltages in said secondary 10 windings and the circulating current therein, whereby said signal means indicates the condition of said track section.

15 8. In combination, an impedance device, and means for energizing said device; said means comprising a source of alternating current, phase controlled voltage regulating means connected with said source and operative to provide balanced potentials at the output thereof, and means

for connecting said impedance device across said balanced potential output for introducing a phase displacement in said phase controlled voltage regulating means for producing a difference of potential proportional to the phase displacement for energizing said device. 5

9. The combination set forth in claim 8 and including means for shunting said device for effectively removing said phase displacement and reducing said potential difference substantially 10 to zero, whereby current in said shunting means is substantially zero.

10. The combination set forth in claim 8 and including means for shunting said device for effectively removing said phase displacement 15 and reducing said potential difference to zero, the last said means comprising the rails of a track section in a railway block signal system and electrically bonded means carried by a train on said rails in bridging relation thereto, whereby 20 said device is deenergized under control of a train in said track section.

JOHN C. McDONALD.
